UNITED STATES PATENT OFFICE.

HENRY L. A. FRANK, OF PLAINVIEW, TEXAS.

DISPLAY DEVICE.

1,345,158.

Specification of Letters Patent. Patented June 29, 1920.

Application filed March 25, 1919. Serial No. 285,092.

To all whom it may concern:

Be it known that I, HENRY L. A. FRANK, a citizen of the United States, residing at Plainview, in the county of Hale and State of Texas, have invented certain new and useful Improvements in Display Devices; and I do hereby declare the following to be a full, clear, and exact description of the invention, such as will enable others skilled in the art to which it appertains to make and use the same.

This invention relates to improvements in display devices, and has for one of its objects the provision of a device of this character especially adaptable for displaying wearing apparel and the like, and one that will not require a great amount of space and which will be out of the way when not examining the articles thereon.

Another object of this invention is the provision of an apparel-supporting member having means attached thereto for suspending it from the ceiling of a room and is capable of being lowered when desiring to examine the article thereon, and which will automatically return to an elevated position out of the way when released.

A further object of this invention is the provision of a display device of the above stated character, which shall be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described, and claimed.

For a complete understanding of my invention, reference will be had to the following description and accompanying drawings, in which:

Figure 1 is a front elevation of a display device constructed in accordance with my invention.

Fig. 2 is a fragmentary vertical sectional view of the same,

Fig. 3 is a plan view, illustrating the article-supporting member,

Fig. 4 is a detail sectional view of a form of flange carried by the article-supporting member,

Fig. 5 is a fragmentary sectional view,

illustrating a hook carried by the article-supporting member,

Fig. 6 is a detail sectional view, illustrating a form of clamp carried by the article-supporting member,

Fig. 7 is a vertical sectional view of means for normally supporting the article-supporting member in an elevated position,

Fig. 8 is a transverse sectional view of the same, taken on the line 8—8 of Fig. 7,

Fig. 9 is a similar view, taken on the line 9—9 of Fig. 7.

Referring in detail to the drawing, the numeral 1 indicates as an entirety an article-supporting member consisting of a ring or hoop 2 having secured thereon spring actuated clasps 3 for attaching collars and similar wearing apparel to the ring or hoop 1. A plurality of hooks 4 are secured to the ring or hoop 2 from the inner face thereof from which may be suspended waists, shirts or other apparel that are usually placed upon garment hangers. Resilient straps 5 are secured to the outer face of the ring or hoop 2, as shown at 6, and have their free ends bent to form finger grips 7 adapted to form clasps or grips for securing neckties and like wearing apparel to the ring or hoop. A plurality of chains 8 or flexible elements have one of their ends secured to the rim or hoop 2, as illustrated at 9, while their opposite ends are secured to a plate 10 carrying a hook 11 and a loop 12.

A rod 13 is formed upon one end with an eye 14 and receives a hook 11, and has mounted thereon a slidable collar 15 on which is positioned a coil spring 16. The other end of the coil spring 16 bears against a collar 17 fixed upon the rod 13 and engages one end of a casing 18, as illustrated in Fig. 7. The casing 18 is of hollow formation and has its lower end closed by a cap 19 provided with an opening to slidably receive the rod 13 permitting the collar 17 to bear against the same. The cap 19 may be secured to the casing 18 in any well known manner, and has positioned thereon a coil spring 20 located within the casing 18 and has its other end disposed against the partition 21 carried by the casing. A partition 22 is carried by the casing at the outer end thereof and coöperates with the partition 21 in supporting a tube 23. The

tube 23 receives in its lower end the upper end of the rod 13 to which is connected a chain or flexible element 24, which extends outwardly of the casing 18 and passes over 5 a pulley 25 carried by a bracket 26, which is adapted to be secured to the ceiling. The chain, or flexible element 24, after passing over the pulley 25 is connected to a bail 27 secured to the upper end of the casing. The 10 partition 22 is provided with an opening 28 so that lead or other similar heavy material may be placed within the casing 18, as desired, for increasing and decreasing the weight thereof. The casing 18 is adapt- 15 ed to be weighted to a degree that will overcome the weight of the article carried by the article-supporting member 1, so that the article-supporting member is supported in an elevated position, the casing 18 pull- 20 ing the same upwardly. A chain or flexible element 29 is secured to the loop 12 and is adapted to depend downwardly therefrom within reach of a person, so that the article- 25 supporting member 1 may be lowered for the purpose of examining or inspecting the articles carried thereby. When the chain or flexible element 29 is released, the casing 18 moves downwardly pulling upwardly the article-supporting member 1, and as the cas- 30 ing 18 moves downwardly it engages the col- 35 lar 17, causing the same to compress the spring 13 and the spring twining absorbing the shock or jar of the casing reaching its lowermost position.

35 While I have shown and described the

preferred embodiment of my invention, it will be understood that minor changes in construction, combination and arrangement of parts may be made without departing from the spirit and scope of the invention 40 as claimed.

Having thus described my invention what I claim is:

A display device comprising a tubular casing, spaced partitions in said casing, a 45 tube extending through the partitions and forming a weight chamber between itself and the partitions and casing, one of said partitions having an opening to permit heavy substance to be placed in and removed from 50 the weight chamber, a flexible element se- 55 cured to one end of the casing and passing over a supported pulley and downwardly in said tube, a cap closing the lower end of said casing and having an opening therein, a rod extending through the opening of 60 said cap and into the tube and connected to the flexible element, an apparel attaching element secured to said rod, a cushioning means on said rod between the cap and the apparel attaching element, and a flexible element connected to said rod depending be- 65 low the apparel attaching element.

In testimony whereof I affix my signature in presence of two witnesses.

HENRY L. A. FRANK.

Witnesses:

CLAUDE POWER,
WILL STOCKTON.
